[57] CLAIM

The ornamental design for a laptop computer cart, as shown and described.

DESCRIPTION

FIG. 1 is a perspective view of a laptop computer cart according to our new design with a desktop of the computer cart in the closed position;

FIG. 2 is a front elevational view of the laptop computer cart of FIG. 1, the front view of the laptop computer cart with the desktop in the open position being identical thereto;

FIG. 3 is a back elevational view of the laptop computer cart of FIG. 1, the back elevational view of the laptop computer cart of FIG. 1 with the desktop in the open position being identical thereto;

FIG. 4 is a side elevational view of the right side of the laptop computer cart of FIG. 1, the opposite side being a mirror image thereof;

FIG. 5 is a top plan view of the laptop computer cart shown in FIG. 1;

FIG. 6 is a bottom plan view of the laptop computer cart shown in FIG. 1;

FIG. 7 is a perspective view of the laptop computer cart of FIG. 1 with the desktop of the laptop computer cart in the open position;

FIG. 8 is a side elevational view of the right side of the laptop computer cart of FIG. 7, the opposite side being a mirror image thereof;

FIG. 9 is a top plan view of the laptop computer cart shown in FIG. 7; and,

FIG. 10 is a bottom plan view of the laptop computer cart shown in FIG. 7.
